UNITED STATES PATENT OFFICE.

GEORGE H. FLETCHER, OF DETROIT, MICHIGAN.

CAR-BRAKE.

SPECIFICATION forming part of Letters Patent No. 408,877, dated August 13, 1889.

Application filed November 30, 1888. Serial No. 292,285. (No model.)

To all whom it may concern:

Be it known that I, GEORGE H. FLETCHER, a citizen of the United States, residing at Detroit, county of Wayne, State of Michigan, have invented a certain new and useful Improvement in Car-Brakes; and I declare the following to be a full, clear, and exact description of the invention, such as will enable others skilled in the art to which it pertains to make and use the same, reference being had to the accompanying drawings, which form a part of this specification.

My invention relates to that class of car-brakes which are adapted more especially for use on street-railway cars; and it consists of a combination of devices constituting my invention, which is utilized to set the brakes.

In the drawings, Figure 1 is an inverted plan view of a car-truck with my device attached thereto. Fig. 2 is an end elevation of a car, showing the lever used to throw the brakes into operation. Fig. 3 shows a detailed view of a part, and Fig. 4 shows an inverted plan view of a variation.

25 In the above drawings, A represents the truck-wheels, and B the truck-frame, of a car.

C C' are the draw-bars, to which the whiffle-tree may be attached. D D' are the brake-beams, to which the brake-shoes E E' are attached, and e e' are the usual links supporting the shoes. These brake-beams are divided midway between the wheels and the inner ends pivotally engaged to the draw-bars C C'.

35 F F' are levers. They are pivotally engaged at their ends to the inner ends of the draw-bars and extend inwardly therefrom in a diagonal direction to the plates G G', where they are fulcrumed at g. The short arms f of these levers are connected by adjustable connections with the outer ends of the brake-beams. These adjustable connections may be chains, or, as shown, they may be composed of two rods H, connected by the turn-buckle h. The plates G G' are supported by the cross-bars b of the truck-frame, and are provided with ears g', which project downward and loosely embrace the rod b'. It will be seen that the plates G G' will thus have

45 an inward or lateral motion.

I I' are levers pivotally engaged to the frame-work J, which is in turn rigidly en-

gaged to the truck-frame. At i these levers are pivotally engaged to the draw-bars.

K are bell-crank levers fulcrumed at k to the frame-work J, and having one arm k' attached to the lever L, which extends upward above the platform of the car. The other arm k² is provided with the slot k³, in which works a pin on the end i' of the lever I. 60 When the brakes are off, the end i' of the lever I rests in a small recess at the end of the slot k³ and can only be released by a throw of the lever I and a consequent movement of the bell-crank. 65

M is a rod extending from the end i² of the lever I to the other end of the truck, where it is engaged to the lever I' at the point where the latter is engaged to the draw-bar, and M' is a corresponding rod extending from the lever I at the point where the latter is engaged with the draw-bar to the opposite end of the truck, where it engages with the end i³ of the lever I'. Thus the levers I I' will be caused to move simultaneously. 70

The operation of the apparatus will now be understood. By a throw of the lever L the operator releases the end i' of the lever I and moves it forward, thus giving a like movement to the draw-bar. The draft of the horses 80 on the draw-bar when it is released will also tend to move the latter forward. This forward movement or pull of the draft-bar draws the ends of the levers F forward, and this, together with the inward motion of the plates 85 G G', to which they are fulcrumed, causes the short arms f to exert a strong pull on the brake-beams, with which they are connected by the rods H, and operates to set the brakes. The motion of the lever I is simultaneously 90 transmitted to the lever I' by the rod M', and the brakes on each end of the truck are thus operated simultaneously. It will thus be seen that by connecting the draft-bar with the brakes the motion of the former is utilized 95 and the resistance of the car operates to set the brakes.

100 Springs N may be attached to the truck-frame and to the plates G G' and serve to assist in returning the plates to their normal position and thus release the brakes.

Of course, if desired, only that apparatus necessary to set the brakes on two of the wheels need be employed; but, ordinarily, I

would construct the apparatus, as shown, so that the brakes could be operated from either end. So, also, if desired, the plates G G' might be suspended from a single rod instead of sliding in the frame-work, as shown; or the rod b' may be dispensed with and the plates G G' be sustained and guided entirely by the cross-bars b.

It is evident that a construction wherein the outer ends of the levers F F' are engaged to separate bars or rods that extend to the levers I I' and the latter connected to the ordinary hand-brake staff would be contemplated by me. In this latter construction the brakes would be set entirely by the driver irrespective of the draft-power.

If desired, the rods M M' may be made adjustable by providing them with turn-buckles m m'.

The levers I I' and bell-crank levers K may, if desired, be pivoted directly to the car-bottom or to the truck-frame, the frame J being employed or not, as the construction of the car-truck demands.

It is evident that my invention would also contemplate a construction, as shown in Fig. 4, in which the levers F F' are fulcrumed to a stationary point and the forward ends provided with slots f², in which pin f³ on the draw-bar would slide. In this variation it is evident that the same result would be accomplished—*i. e.*, the inward pull of the short arms f of the levers F F' operating directly on the ends of the brake-beams. In this variation the springs N may be located at the ends of the draw-bar, as shown.

What I claim is—

1. In a car-brake mechanism, the combination, with the draw-bar and brake-beams having their inner ends pivoted to said draw-bar, of pivoted levers, each having its short arm linked to its corresponding brake-beam and each having its long arm engaged with the draw-bar, the construction being such that a pull upon the draft-bar will tilt said levers and draw the brake-shoes to their seats, substantially as described.

2. In a car-brake mechanism, the combination, with the draw-bar and brake-beams having their inner ends pivotally connected with said draw-bar, of pivoted levers, each having its short arm linked to its corresponding brake-beam and each having its long arm engaged with the draw-bar, the construction being such that a pull upon the draft-bar will tilt said levers and draw the brake-shoes to their seat, and, in connection with the above

means, to retract the shoes to their initial position when the draft ceases, substantially as described.

3. In a car-brake, the combination, with the brake-beams, of levers having their short arms linked with their corresponding brake-beams and their long arms connected with the draft-bar or brake-rod, said levers fulcrumed to two plates adapted to slide laterally, the construction being such that a pull on the outer ends of the levers operates to draw in the plates and throw back the short arms of the levers, so that a tension is exerted directly on the brake-beams and the brakes set, substantially as described.

4. In a car-brake mechanism, the combination, with the brake-beams, of levers having their short arms linked with their corresponding brake-beams and their long arms connected with the draft-bar or brake-rod, said levers fulcrumed to two plates adapted to slide laterally, and springs adapted to return the plates to their normal position when the draft-power ceases, substantially as described.

5. A car-brake consisting of a brake-beam divided midway between the wheels, the ends pivotally engaged to the draw-bar, and the opposite ends provided with shoes adapted to bear on the wheels, and two levers pivotally engaged at their outer ends to the draw-bar and fulcrumed to two plates adapted to move laterally, the short arms of said levers being connected by rods with the outer ends of the brake-beams, the construction being such that an outward movement of the draw-bar operates to set the brakes, substantially as described.

6. In a car-brake, the combination, with the brake-beam, the levers F, plates G G', and rods H, of the levers F', fulcrumed to the opposite sides of the plates G G', the connecting-rods M M', and levers I I', whereby the brakes are simultaneously set on both sets of wheels, substantially as described.

7. A car-brake consisting of the combination, with the brake-beams and shoes and the draw-bars, of the levers F F', rods H, plates G G', springs N, levers I I', rods M M', bell-crank levers K, and levers L, all arranged substantially as and for the purposes described.

In testimony whereof I sign this specification in the presence of two witnesses.

GEORGE H. FLETCHER.
